UNITED STATES PATENT OFFICE.

WILLIAM E. BEATTY, OF BAYSIDE, NEW YORK, ASSIGNOR TO WESTERN ELECTRIC COMPANY, INCORPORATED, OF NEW YORK, N. Y., A CORPORATION OF NEW YORK.

REPEATER SYSTEM.

1,426,810.

Specification of Letters Patent. Patented Aug. 22, 1922.

Application filed September 30, 1918. Serial No. 256,248.

To all whom it may concern:

Be it known that I, WILLIAM E. BEATTY, a citizen of the United States, residing at Bayside, Long Island, in the borough of 5 Queens, State of New York, have invented certain new and useful Improvements in Repeater Systems, of which the following is a full, clear, concise, and exact description.

10 The invention relates to a telephone system in which a one-way repeater is reversibly connected to the line to provide for the two-way transmission of signals.

An object of the invention is to establish 15 the repeater connections automatically in response to current such as voice current impressed on the line. The invention provides for each of the two lines a control relay operated preferably by voice current. A further object of the invention is to insure that 20 signaling current approaching the repeater in one direction shall operate the proper voice relay and not the other relay. This is accomplished by a short circuit across the 25 line and located between the two relays. Current approaching the repeater from either direction after passing one relay is short-circuited and thereby prevented from reaching the other relay. The short circuit 30 is automatically removed from across the lines and connected across the relay, which should not be operated, so that the latter is rendered inoperative and the control maintained by the proper relay. One of the relays 35 is associated with the output side of the repeater, whereby the current which operates it is amplified by the repeater, thereby avoiding the necessity of a separate amplifier for this purpose.

40 For further details reference may be made to the drawings, in which Fig. 1 shows one embodiment of the invention; and Fig. 2 illustrates a conventional audion amplifier.

45 In Fig. 1 of the drawings, the repeater 1, which is here shown as of the mechanical type, although any other type may be used instead, is shown to be reversibly connected between the lines 2 and 3 to provide for the 50 two-way transmission of signals. The connection of the repeater 1 to the lines 2 and 3 is made through electromagnetic switches 4 and 5 which are controlled by the relays 6 and 7, the latter two being in turn controlled by the control relay 8. The circuit

connections are also controlled by a relay 9 similar to the relay 8. If desired, the relay 8 may be provided with an amplifier A shown in detail in Fig. 2. It is unnecessary to provide an amplifier for the relay 9 since the current which operates it will be amplified by the repeater 1. The relays 8 and 9 are responsive to alternating or pulsating current, such as voice current, to cause vibration of their normally closed contacts 10 and 11 respectively. The invention is not limited to any particular form of voice relay and as illustrating one type of relay that may be employed, reference is made to the patent to Brown, 1,185,472, May 30, 1916. 70

The repeater 1 is normally connected to the lines 2 and 3 but cannot transmit current therebetween because of the shunt 16. With the switch contacts in the position shown in drawings, this transmission may take place in the direction from the line 2 to the line 3, after the short circuit 16 has been removed. The circuits may be traced as follows: line 2, armature 12, input side of the repeater, armature 14, other side of the 80 line 2. The current coming in over the line 2 after actuating the repeater 1 and being thereby amplified actuates relay 9 and sets the contact 11 into vibration. The vibration of contact 11 sufficiently increases the resistance in circuit with switch 15 so that the latter drops its armature 16, thereby removing the short circuit from the output side of the repeater and placing this short circuit across the relay 8, which is thereby 85 rendered inoperative. With the armature 16 in its lowermost position, the repeater 1 may deliver amplified current through the armatures 17 and 18 out upon the line 3. 90

The location of the short-circuiting armature 16 between the relays 8 and 9 insures that if the relay 9 operates first, this relay will maintain control of the connections, the relay 8 being rendered inoperative. If voice current originates in line 3, it is 100 necessary that the connections of the repeater 1 to the lines be reversed, in order that current may be repeated from line 3 to line 2. This reversal of connections takes place as follows: current coming 105 in over the line 3 takes a circuit through armature 17, then through armature 16 which is in parallel with a circuit including the secondary of repeating coil 19 and relay 9, to voice relay 8 and armature 18 110

to the other side of line 3. Substantially all of the current passes through armature 16, and relay 9 is not operated. The energization of relay 8 sets its contact 10 into vibration, which sufficiently increases the resistance in circuit with solenoid 20 of relay 6 so that the armature 21 assumes its alternate position. The circuit for the solenoid 20 may be traced as follows: from ground through contact 10, lead 22, armature 23, solenoid 20, battery 24 to ground. The armature 21, when in its alternate position, connects the battery 24 to the solenoids of switches 4 and 5, thereby energizing these switches and reversing the connections of the repeater 1 to the lines 2 and 3. The armature 21 in its alternate position also connects the battery 24 over lead 25 through solenoid of relay 7 to ground, thereupon moving armatures 23 and 26 to their alternate positions. This disconnects the ground 27 from solenoid 28 of relay 6 and connects solenoid 28 to ground over the lead 22 and through the vibrating contact 10. The inward movement of armature 23 removes the solenoid 20 from the control of the contact 10 and connects the solenoid 20 to ground 29. This shift in the control of vibrating contact 10 with respect to the solenoids 20 and 28 of relay 6 is made necessary by reason of the fact that, the switches 4 and 5 being energized due to the armature 21 assuming its alternate position, the repeater is connected to transmit current in the reversed direction between the lines 2 and 3, with respect to the direction it could transmit current between these lines with the connections as shown in the drawings. With the output side of the repeater connected to line 2, current originating in this line and approaching the repeater will reverse the repeater connections as desired.

Still considering the case where voice current originates in the line 3 with the repeater connections as shown in the drawings, the relay 8 having operated, the connections of the repeater 1 to the lines 2 and 3 is reversed as previously described, current coming in over the line 3 now passes through the armatures 12 and 14 to the input side of the repeater and from the output side of the same through armatures 17 and 18 to the line 2. The voice relay 9 then operates as previously described to remove the short circuit from across the output side of the repeater, short-circuiting relay 8, thereby rendering it inoperative. The relay 9 continues to maintain control of the connections as long as current comes in over the line 3. When current in the line 3 ceases, the contact 11 becomes quiet and the short circuit including armature 16 is removed from relay 8 and is connected across the output side of the re-

peater. The repeater then remains in condition to transmit current in a direction from line 3 to line 2. In case current subsequently originates in line 2, the repeater connections are reversed as has been previously described. 70

What is claimed is:

1. The combination of two lines, a repeater adapted to be reversibly connected therebetween, means for controlling the connection of said repeater to said lines and for connecting said repeater in position to transmit currents in one direction over said lines in the absence of signaling current in said lines, said means comprising 75 a relay connected to the output side of said repeater for energization by amplified currents from said repeater. 80

2. The combination of two lines, a repeater, means for reversibly connecting said repeater between said lines and for connecting said repeater in position to transmit currents in one direction over said lines in the absence of signaling current in said lines, a relay responsive to current approaching the repeater in either direction for controlling said repeater, and connections for energizing said relay with amplified current from said repeater. 90

3. A repeater system comprising two 95 lines, a single amplifying path adapted to be reversibly connected therebetween and comprising a repeater, two relays in the output circuit of said repeater for controlling the repeater connections, and a controllable short circuit between said relays. 100

4. A repeater system comprising two lines, a single amplifying path adapted to be reversibly connected therebetween and comprising a repeater, two relays in the output circuit of said repeater for controlling the repeater connections, and a short circuit between said relays and adapted to be controlled by one of said relays. 105

5. A repeater system comprising two 110 lines, a unidirectional current conducting amplifying means, switches and input and output amplifier leads for reversibly connecting said means to said lines, electromagnetic means for controlling said switches, and a relay responsive to amplified current from said amplifying means for controlling said electromagnetic means, said switches comprising contacts connected to said lines and armatures connected to said leads. 115 120

6. A line, a repeater, means for connecting said repeater to said line throughout the absence of signaling current from the line and for operatively associating either the input side or the output side of said repeater with said line, and means responsive to amplified current from said repeater for controlling said first mentioned means. 125

7. A repeater system comprising a line, a repeater therefor, a circuit in shunt to said 130

- line, and means responsive to amplifying current from said repeater for controlling said circuit, said means comprising a contact vibrating while currents are being transmitted in one direction through said repeater, and said shunt circuit being between the output side of said repeater and a distant station.
8. A repeater system comprising a line, 10 a repeater therefor, a circuit in shunt to the output side of said repeater and means responsive to amplified current from said repeater for controlling said circuit, said shunt circuit being between the output side 15 of said repeater and a distant station, and being closed when not transmitting.
9. A repeater system comprising a line, an energy amplifying repeater therefor, a relay responsive to current impressed on 20 said line, a circuit in shunt to said relay, and means responsive to amplified current from said repeater for controlling said circuit said shunt circuit being between the output side of said repeater and a distant station.
- 25 10. A line, an energy amplifying repeater therefor, a relay in the output circuit of said repeater, a movable contact for connecting said relay into or out of circuit, and means responsive to amplified current from said repeater for controlling said contact said movable contact being between the output side of said repeater and a distant station.
11. The combination of two lines, a repeater therebetween, a relay responsive to current originating in one of said lines but initially unresponsive to current coming in over the other of said lines, and means responsive to current impressed on said other line to reverse the connections of said repeater with respect to said lines whereby said initially unresponsive relay is finally responsive to current impressed on said other line after it has actuated said repeater.
12. The combination of two lines, a repeater therebetween, a plurality of relays for controlling the connections of said repeater to said lines, both of said relays being in the output circuit of said repeater, and means comprising a movable armature for rendering one of said relays unresponsive to current approaching the input side of said repeater while permitting the other relay to respond to current approaching the output side of said repeater.
13. The combination of two lines, a repeater adapted to be reversibly connected therebetween, a plurality of relays for controlling the connections of said repeater to said lines, two of said relays being in the output circuit of said repeater, and means comprising a movable armature for rendering one of said relays unresponsive to current approaching said repeater by way of
- its input circuit and for rendering the other relay unresponsive to current approaching said repeater by way of its output circuit, said relays being otherwise responsive to current approaching said repeater for controlling the connection of said repeater to said lines.
14. A line, a repeater therefor, a relay associated therewith, a movable contact adapted to shunt either the output circuit of said repeater or said relay and a second relay responsive to amplified current from said repeater for controlling said contact.
15. A line, a repeater therefor, a relay associated therewith, a movable contact adapted to shunt either the output circuit of said repeater or said relay, and a second relay responsive to amplified current from said repeater and adapted to remove the shunt from across said output circuit and to place a shunt about said first-mentioned relay.
16. Two lines, a repeater, switching mechanism for reversibly connecting said repeater to said lines, a relay controlling said switching mechanism and comprising two solenoids, a relay having a movable contact, means for interchangeably connecting said movable contact in circuit with one or with the other of said solenoids whereby the repeater connections are reversed when incoming current approaches the repeater by way of its output circuit, and means responsive to amplified current from said repeater for controlling said relay having a movable contact.
17. Two lines, a repeater, switching means for reversibly connecting said repeater to said lines, a relay for operating said switching means, and means comprising a second relay responsive to amplified current from said repeater for rendering said first-mentioned relay inoperative.
18. A two-way repeater system comprising two lines, a repeater normally connected thereto, reversing switching contacts in the input circuit and in the output circuit of said repeater, electromagnetic means controlling said contacts, and a plurality of relays between said repeater and said output circuit contacts for controlling said electromagnetic means, and connections whereby one of said relays is adapted to control the operation of the other relay.
19. A two-way repeater system comprising two lines, a repeater adapted to be reversibly connected thereto, and means comprising a single voice operated relay device responsive to amplified current from said repeater for reversing the repeater connections for transmission in either direction between said lines.
20. A line, a repeater, means for operatively associating either the input side or the output side of said repeater with said line, and means responsive to amplified cur-

- rent from said repeater for controlling said first mentioned means, the second mentioned means comprising a single relay armature and circuit connections controlled thereby 5 whereby in one position of said armature the first mentioned means is caused to connect the input side of said repeater to said line, and in another position of said armature the first mentioned means is caused to connect 10 the output side of said repeater to said line.
21. The combination of two lines, a repeater, means for reversibly connecting said repeater between said lines, and means comprising a relay for controlling the connection 15 of said repeater to said lines, said relay being connected to the output side of said repeater for energization by amplified currents from said repeater, said first mentioned means comprising incoming and outgoing 20 repeater leads and electromagnetic switches having armatures connected to said leads and having contacts connected to said lines.
22. A combination of two lines, a repeater adapted to be reversibly connected therebetween and means comprising a relay for controlling the connection of said repeater to said lines, said relay being connected to the output side of said repeater for energization 25 by amplified currents from said repeater, and said means comprising a single relay armature and circuit connections controlled thereby whereby in one position of 30 said armature said repeater is adapted to transmit currents in one direction and in another position of said armature said repeater is adapted to transmit currents in 35 the reverse direction.
23. The combination of two lines, a repeater, means for reversibly connecting said repeater between said lines, a relay responsive to current approaching said repeater in either directions for controlling said repeater, and connections for energizing said relay with amplified current from said repeater, said first mentioned means comprising incoming and outgoing repeater leads and electromagnetic switches having armatures connected to said leads and having contacts 40 connected to said lines. 45
24. A repeating system comprising a line, a repeater, means for operatively associating either the input side or the output side of said repeater with said line, a plurality of alternating current relays for controlling 50 said means, one of said relays being responsive to amplified current from said repeater, and means comprising connections whereby one of said relays renders another of said relays inoperative. 55
25. A repeating system comprising two lines, a single amplifying path comprising a repeater, switch contacts for reversibly connecting said repeater between said lines, an alternating current relay responsive to 60 amplified current from said repeater, a second alternating current relay, means comprising said relays for controlling said contacts and means comprising connections whereby one of said relays renders the other 65 of said relays inoperative. 70

In witness whereof, I hereunto subscribe my name this 18th day of September A. D., 1918.

WILLIAM E. BEATTY.
